(57) **CLAIM**

The ornamental design for a handle for a medical delivery device, as shown and described.

DESCRIPTION

All of the material from the Application for a registered Community design which is essential to the claimed design is included herein. Any material in the Application for a registered Community design which is not present herein forms no part of the claimed design.

FIG. 1 is a right, top and front perspective view of a handle for a medical delivery device showing our new design;

FIG. 2 is a top plan view thereof;

FIG. 3 is a bottom plan view thereof;

FIG. 4 is a right side view, the left side view being a mirror image thereof;

FIG. 5 is a front elevational view thereof; and,

FIG. 6 is a rear elevational view thereof.

The broken lines in FIG. 4 are for illustrative purposes only and form no part of the claimed design.
